UNITED STATES PATENT OFFICE.

CHARLES MARK JACOBS AND ROBERT JAMES INSELL, OF READING, EDWARD FRANK NEWTON, OF CARDIFF, AND ERNEST ALBERT BENNETT BOWDEN, OF HANWELL, ENGLAND, ASSIGNORS TO THE WESTERN SYNDICATE LIMITED, OF LONDON, ENGLAND.

SIGNALING ON RAILWAYS.

No. 833,603.

Specification of Letters Patent.

Patented Oct. 16, 1906.

Application filed October 30, 1905. Serial No. 285,163.

To all whom it may concern:

Be it known that we, CHARLES MARK JACOBS, residing at St. Cuthberts, Alexandra Road, Reading, in the county of Berks, ROBERT JAMES INSELL, residing at 17 Russell street, Reading, in the county of Berks, EDWARD FRANK NEWTON, residing at 123 Claude road, Roath Park, Cardiff, in the county of Glamorgan, and ERNEST ALBERT BENNETT BOWDEN, residing at 21 Balfour avenue, Hanwell, in the county of Middlesex, England, subjects of the King of Great Britain, have jointly invented certain new and useful Improvements in or Relating to Signaling on Railways, of which the following is a specification.

It has frequently been proposed to signal between fixed points on a railway-line and trains passing along the line by means of some device at the fixed point which will operate a signal on the passing train.

The present invention relates to this method of signaling; and it consists in an arrangement whereby when the train passes the fixed points a device on the train for giving a signal is invariably operated, while whenever information other than that conveyed by this signal is to be imparted a supplementary signal is given.

For well-known reasons it is preferable that the device invariably operated should give a signal accepted as a danger-signal, while the supplementary signal should be accepted as the all-right signal. It is also preferable that although the device for giving the danger-signal is invariably operated the actuation of the all-right signal should cancel or suppress the actual indication of the danger-signal, for in this manner all chance of confusion between the two signals is avoided. The invention, however, is not limited to this acceptance of the meaning of the two signals or to the suppression of the invariably-operated signal when the supplementary signal is given, it being practicable to avoid confusion by the use of signals of very different kind, such as a visible signal for one and an audible signal for the other.

The accompanying drawings illustrate, by way of example, one form of apparatus according to the invention applied to a train

carrying a steam-boiler or a reservoir of compressed air.

Figure 1 is a side elevation, and Fig. 2 an end elevation, of a railway-locomotive fitted with devices according to this invention and shown running on a track provided with a device for operating the signals. Fig. 3 is an elevation, drawn to an enlarged scale, to show the details of the signals.

In this instance the danger-signal is a steam-whistle *a* on the locomotive *b*, and the all-right signal consists of both the suppression of the sounding of the whistle and the ringing of a bell *c*.

The whistle *a* is mounted on a steam-pipe *d*, proceeding from the boiler, and is controlled by a valve *d'*, which is normally kept closed by a lever *e*, on an inclined surface of which bears a roller *f* on the short arm of a bell-crank lever *f'*, to the other arm of which is fixed the armature *g* of an electromagnet *h*. This electromagnet has two windings, one of which is connected at one end by lead *i'* with one terminal *k'* of a switch *k*, fixed to the underframe *l* of the locomotive, while the other end is connected by lead *i''*, through contacts *i³* *i⁴* (the purpose of which will presently be explained) and lead *i⁵*, with one pole of a suitable battery *i* on the locomotive, the other pole of which battery is connected with the other terminal *k²* of the switch.

When the locomotive is running between the fixed points on the tracks, the terminals *k' k²* of the switch *k* are bridged by an arm *m*, mounted on a shaft *n*, which turns in suitable bearings *n'*, carried by brackets *l'*, bolted to the underframe *l*. Also fixed on the shaft *n* is a lever *o*, one end of which bears on the top of a spring-pin *p* and is thus normally kept against a cross-bar *l²*, bolted to the brackets *l'*. The other end of lever *o* is connected by an adjustable link *q* with a lever-arm *r*, which is fixed to a shaft *s*, also turning in bearings carried by the brackets *l'*.

At each fixed point in the track there is fixed between the rails a ramp *t*, having on its surface an insulated metal rail *t'*.

The brackets *l'* are insulated from the underframe *l*, and attached to one of them is a spring *u*, which rubs against a collar *s'* on the shaft *s* and is electrically connected, through

the bracket l' , on which it is mounted, with a terminal v on the base of the switch k .

Reverting to the second winding on the magnet h , one end of this is connected by lead v' with the terminal v , while the other end is connected by lead v^3 with earth through the frame of the locomotive and the running-rail. A branch v^2 of the lead v' is connected with one terminal of the electric bell c , the other terminal of which is connected with earth.

Whenever the locomotive passes over a ramp t in the track, the lever r is lifted thereby and the switch-arm m is turned to open the circuit of the battery i . The magnet h is thus deenergized, and the armature g drops until it rests on the stop g' . The pressure on the lever e is thus relieved and the steam blows open the valve of the whistle a , which is consequently sounded. This signal is accepted by the driver as a danger-signal. As soon as the locomotive has passed the ramp t the spring-pin p returns the lever r , and the circuit of the electromagnet h is reestablished.

Thereupon the driver turns the handle f^2 to bring the armature g into position against the magnet. If the line is clear, before the train has arrived at the place where ramp t is fixed the signalman will have closed a switch w . The effect of this is that when the train arrives at the ramp and the lever r makes contact with the rail t' an electric circuit is established from one pole of a battery x , situated beside the track, through rail t' , lever r , spring u , terminal v , lead v' , the second winding of magnet h , and through earth to the other pole of battery x , which is also earthed. A current is thus passed through the second winding of magnet h , so that the armature g is

prevented from falling, or, if it has begun to fall owing to the breaking of the circuit including the first winding, is immediately brought back into its raised position. Thus the whistle a is not sounded, although the lever r is raised and the arm m is turned to interrupt the circuit of battery i . As already stated, the circuit that includes the second winding of magnet h is branched to include also the electric bell a , which is therefore sounded when switch w is closed, indicating to the driver that the line is clear.

In order to avoid waste of current when the locomotive is not in use—that is to say, when the steam-pressure in its boiler is below a certain value—the steam-pipe d is branched, the branch d^2 opening into a small cylinder y , in which is a diaphragm y' of elastic material covering a steel spring y^3 , which presses against a plunger z , passing through the cover y^2 of the cylinder y and bearing against a spring-contact i^4 , already referred to as being in the circuit of the first winding of magnet h . The spring of the plunger is, however, sufficiently powerful to overcome a certain pressure—say twenty pounds—of steam

in the steam-pipe d^2 . It follows that contacts i^4 and i^3 do not come together to close the circuit of the first winding of magnet h unless the steam-pressure in the locomotive-boiler exceeds, say, twenty pounds—that is to say, 70 unless the locomotive is in use.

Although a specific construction has been hereinbefore described for the purpose of practicing this invention, it is to be understood that the latter is not limited in any way 75 to such construction. It will be obvious to any mechanical engineer how the two signals on the train may be operated by mechanical appliances solely or by a combination of mechanical and electrical appliances actuated 80 by a device or devices in the track. It is also obvious that pneumatic transmission may be substituted for electric transmission and that for the audible signals may be substituted visible signals or for one of the signals the operation of an air-brake. 85

Having thus particularly described and ascertained the nature of our said invention and the best means we know of carrying the same into practical effect, we claim— 90

1. A signaling device for railways, comprising means constituting a normally closed circuit, means constituting a normally open circuit, a single electrical device contained in both circuits, a danger-signal controlled by 95 said electrical device, a safety-signal contained in the said normally open circuit, mechanical means for opening said closed circuit to give the danger-signal when the train passes a signaling-point, and means for closing said normally open circuit to restrain the danger-signal and at the same time give the safety-signal.

2. Apparatus for signaling between fixed points on a railway-line and a train passing 105 along the line, comprising two signals on the train, restraining means for preventing normally one of the said signals being given, means at each fixed point for invariably removing the said restraining means, means at 110 each fixed point for operating the other of the said signals when desired, and means whereby the first of the said signals is suppressed when the second of the said signals is operated.

3. Apparatus for signaling between fixed points on a railway-line and a train passing along the line, comprising a signal on the train, electrically-operated restraining means for preventing normally this signal being 120 given, means at each fixed point for invariably rendering inoperative the said restraining means, and a device at each fixed point for supplying electric current to the said electrically-operated restraining means when 125 desired.

4. Apparatus for signaling between fixed points on a railway-line and a train passing along the line, comprising two signals on the train a ramp at each fixed point, a lever car- 130

- ried by the train in such a position that it is operated by the said ramp, means connected with the said lever for operating one of the said signals, and means for completing an electric circuit through the said ramp, lever and second signal to operate the latter.
5. Apparatus for signaling from fixed points on a railway-line to a train passing along the line, comprising two signals on the train, an electromagnetic device controlling one of the said signals, a source of electric current on the train, a switch on the train, a normally closed electric circuit on the train including the said electromagnetic device, source of current and switch, a device at each fixed point for moving the said switch to control the said circuit and a device at each fixed point to operate the other of the said signals when desired.
10. 6. Apparatus for signaling from fixed points on a railway-line to a train passing along the line, comprising two signals on the train, an electromagnetic device controlling one of the said signals, a source of electric current on the train, a switch on the train, an electric circuit on the train including the said electromagnetic device, source of current and switch, a lever on the train connected with the said switch, a ramp at each fixed point to operate the said lever, an insulated conductor on the said ramp, a source of electric current on the line, an electromagnetic device on the train controlling the other of the said signals, a device for conveying electric current from the said insulated conductor to the said electromagnetic device and means for connecting the said source of electric current on the line with the said insulated conductor when required.
15. 7. Apparatus for signaling from fixed points on a railway-line to a train passing along the line, comprising two signals on the train, an electromagnet controlling one of the signals, two windings on the said electromagnet, a source of electric current on the train, a switch on the train, an electric circuit on the train including one of the windings of the said electromagnet, the said source of current and the said switch, an
20. electrically-insulated lever on the said train

connected with the said switch, a ramp at each fixed point to operate the said lever, an insulated conductor on the said ramp where-with the said lever makes contact when operated by the said ramp, a source of electric current on the line, an electromagnetic device controlling the other of the said signals an electric circuit including the said source of current the said insulated conductor, the said insulated lever, the second winding of the said electromagnet and the said electromagnetic device, and means on the line for closing the last-named electric circuit when desired.

25. 8. Apparatus for signaling from fixed points on a railway-line to a train passing along the line, comprising two signals on the train, an electromagnetic device controlling one of the said signals, a source of electric current on the train, a switch on the train, an electric circuit on the train including the said electromagnetic device, source of current and switch, a steam-boiler on the train, a device operated by the steam-boiler when the pressure therein is above a predetermined value to close the said electric circuit, a device at each fixed point for moving the said switch to control the said circuit and a device at each fixed point to operate the other of the said signals when desired.

30. 9. A signaling device for railways of the character referred to, comprising a normally closed circuit, a normally open circuit distinct from the said normally closed circuit, a lever carried by the train and adapted when actuated to open the normally closed circuit, and a fixed ramp for operating the lever, said lever and said fixed ramp constituting a part of the normally open circuit.

In testimony whereof we have signed our names to this specification in the presence of two subscribing witnesses.
